CLAIM

(57) The ornamental design for a nestable trash can, as shown and described.

DESCRIPTION

FIG. 1 is a perspective front view of a nestable trash can; FIG. 2 is a front elevation view of the nestable trash can; FIG. 3 is a rear elevation view of the nestable trash can; FIG. 4 is a left elevation view of the nestable trash can, right elevation view is a mirror image thereof; FIG. 5 is a top elevation view of the nestable trash can; FIG. 6 is a bottom elevation view of the nestable trash can; and, FIG. 7 is an illustrative perspective front view of the nestable trash can thereof. The nestable trash can is shown without the lid in FIG. 7 for convenience of illustration. The broken lines showing additional nestable trash cans in FIG. 7 depict environmental matter and form no part of the claimed design.
